UNITED STATES PATENT OFFICE.

HENRY N. EDENS, OF NEW HOLSTEIN, WISCONSIN.

CARBURETER.

1,137,307.

Specification of Letters Patent.

Patented Apr. 27, 1915.

Application filed June 1, 1914. Serial No. 842,028.

To all whom it may concern:

Be it known that I, HENRY N. EDENS, a citizen of the United States, and resident of New Holstein, in the county of Calumet and

5 State of Wisconsin, have invented certain new and useful Improvements in Carbureters; and I do hereby declare that the following is a full, clear, and exact description thereof.

10 My invention has for its object to provide a simple, economical and effective carbureter capable of producing as efficient atomizing and fuel feeding results in a starting operation as in ordinary running.

15 With the above object in view the invention consists in certain peculiarities of construction and combination of parts as set forth hereinafter with reference to the accompanying drawings and subsequently claimed.

20 So far as I am aware, under the ordinary carbureter constructions now in use, in order to obtain ideal conditions for starting an engine, it would be necessary to utilize a small carbureter and a separate large carbureter for running. To employ two carbureters for the purpose of efficiency is, however, impractical.

25 My invention contemplates, therefore, a construction of carbureter whereby the most efficient results can be obtained both in a starting operation and in running, which results are primarily attained through a simple adjustment.

30 In the carburization of a low grade of fuel the primary requisite is to cause the volume of air to pass over the fuel jet at a high velocity in order that said fuel may be thoroughly atomized. In the ordinary type of standard carbureter, a restricted area of constant diameter around the fuel jet is utilized. Consequently the amount of air passing through the restricted area is much less in cubic feet per minute in a starting operation than in ordinary running. Hence, in starting, an insufficient amount of fuel necessary for a perfect combustible charge is picked up. In order to counteract this tendency in the ordinary type of carbureter, 35 a valve, either automatically or manually controlled, is placed in the air supply intake mouth, thereby increasing the vacuum around the fuel nozzle, resulting in an increasing amount of fuel supply. However, under these conditions the velocity of the air is decreased to such an extent that the fuel is only partially atomized and, as a

consequence, has a tendency to drop to the bottom of the carbureter and be wasted or this oversupply of liquid fuel will be drawn 60 into the engine cylinder and cause flooding.

It is therefore the primary object of my present invention to overcome the objectionable features demonstrated in practice, as above stated.

65

It is also within the scope of my present invention to utilize either a suction feed for the fuel or to utilize a reservoir in which the level of the fuel is maintained by float mechanism or pump. It is also obvious that it 70 can be adapted for use in connection with a constant level fuel supply. The carbureter is also capable of supplying alcohol as a fuel, without any additional changes of construction.

75

In the drawings Figure 1 represents a central sectional elevation through a carbureter embodying the features of my invention, the section being indicated by line 1—1 of Fig. 2; Fig. 2, an inverted sectional view of the 80 same with parts broken away to illustrate certain valve ports, the section being indicated by line 2—2 of Fig. 1, and Fig. 3, a longitudinal sectional view of the carbureter, the same being taken through a plane as 85 indicated by line 3—3 of Fig. 1.

Referring by characters to the drawings, 1 represents a two-part casing, which casing is provided with an air intake channel 2, and a fuel discharge channel 2'. The casing is 90 preferably cylindrical in form and is divided into an air intake chamber 3 and a fuel mixing chamber 3' by a partition 4, which partition is formed with a centrally disposed hub 5 and radial ports 4', the said partition 95 being in the form of a web between the chambers. The hub 5 of the partition is connected to the walls of the casing within the mixing chamber by an arm 5' having a fuel orifice 6 therein. This fuel orifice is 100 controlled by a pin valve 7, which pin-valve passes through a suitable pipe fitting 8 that is provided with a branch-pipe 9 for supplying the fuel oil. Mounted within the hub 5 is a Venturi tube 10 having an orifice 6' 105 that registers with and constitutes a part of the fuel supply orifice 6, the said orifice being in communication with the restricted belt of the tube. The flared intake mouth of the Venturi tube communicates with the air 110 intake chamber 3 and its corresponding flared discharge mouth communicates with the mixing chamber 3'.

Mounted within the air intake chamber 3

is a barrel valve 11 having a pivot-stud 11' that projects through a central aperture of the casing wall, which wall constitutes the bottom of the air intake chamber. The stud 5 has secured thereto an actuating lever 12, which lever is provided with a segmental slot 12' that is arranged to receive a guide-pin 13, the same being extended from the casing. This guide-pin carries a frictional 10 locking mechanism in the form of a coiled spring 14, the same being interposed between washers that are carried by the pin 13, one of which washers is adapted to exert pressure upon the lever. The barrel valve 15 is adjusted about its axis in alinement with the Venturi tube and, when so adjusted, the frictional locking mechanism is sufficient to hold the same in position.

The upper wall 11" of the barrel valve 20 member, shown partly broken away in Fig. 2, is provided with a central aperture which is fitted about the juxtaposed mouth of the Venturi tube and said wall is also provided with radial ports 15, which ports are adapted 25 to register with the partition ports 4', whereby the latter are controlled, it being understood that the upper face of the valve partition 11' is in sliding engagement with the lower face of the chamber partition 4. 30 The side-wall of the barrel valve is also provided with a port 16, which port is adapted to control the air intake channel 2. As shown in the drawings, the proportion of the barrel ports 15 and 16 with relation to 35 the ports they control is such that when the chamber ports 4' of the partition are entirely closed, the port 16, which controls the intake channel 2, is slightly opened.

From the foregoing description it will be 40 understood that when the engine is to be started, the barrel-valve 11 is rotated by means of the hand-lever 12 until the ports 4' of the partition 4 are entirely closed and the port 16 of the valve only partially closes 45 the intake channel 2, there being sufficient opening between said channel and the mixing chamber 3 to permit a slight amount of air in proportion to the full volume to enter said chamber. The parts being in this 50 position upon the suction stroke of the engine piston, a charge is drawn into the cylinder, whereby a sufficient high vacuum is obtained in the carbureter due to the partial closing of the valve port 16 and the 55 complete closure of the mixing chamber ports 4'. Under these conditions all the air for producing the fuel mixture is passed through the Venturi tube and a sufficient high velocity is thus maintained over the 60 fuel supply vent 6' to thoroughly vaporize said fuel. After the engine is started, the ports 4' and 16 are opened simultaneously

to the position shown in Fig. 1, whereby the greater part of the air then passes through the mixing chamber ports 4', thus 65 maintaining a practically constant velocity through the tube 10. Hence it will be seen that, by the employment of a Venturi tube and a single valve mechanism controlling two sets of ports, a simple and effective carbureter is produced having the qualifications of maximum flexibility with reference to its various duties.

I claim:

1. A carbureter comprising a casing having an intake channel and a fuel delivery channel, a ported partition within the casing arranged to divide the same into an air chamber communicating with the air intake channel, and a mixing chamber communicating with the discharge channel, a centrally disposed Venturi tube carried by the partition having its flared intake mouth extending into the air chamber and its flared discharge mouth extending into the mixing 85 chamber, a valve-controlled fuel supply orifice in communication with the restricted belt of said tube, and a rotatory barrel valve mounted in said air chamber provided with a port adapted to co-act with the partition 90 port, and a second port for controlling the air intake channel.

2. A carbureter comprising a casing having an intake channel and a fuel delivery channel, a ported partition within the casing arranged to divide the same into an air chamber communicating with the air intake channel, and a mixing chamber communicating with the discharge channel, a centrally disposed Venturi tube carried by 95 the partition having its flared intake mouth extending into the air chamber and its flared discharge mouth extending into the mixing chamber, a valve-controlled fuel supply orifice in communication with the restricted belt of said tube, and a rotatory barrel valve mounted in said air chamber provided with a port adapted to co-act with the partition 100 port, and a second port for controlling the air intake channel, the ports 105 being so proportioned with relation to each other that when the intake channel is partly open, the partition controlling port is fully closed; whereby air is admitted to the mixing chamber through the tube only.

In testimony that I claim the foregoing I have hereunto set my hand at New Holstein in the county of Calumet and State of Wisconsin in the presence of two witnesses.

HENRY N. EDENS.
